United States Patent

Des. 236,817
Patented Sept. 16, 1975

236,817

AUDIBLE ALARM

Louis P. Sweany, Carmel, Ind., assignor to P. R. Mallory & Co. Inc., Indianapolis, Ind.

Filed Aug. 29, 1973, Ser. No. 392,669

Term of patent 14 years

Int. Cl. D10—06

U.S. Cl. D10—106

FIG. 1

FIG. 2

FIG. 5

FIG. 3

FIG. 4

FIG. 6

FIG. 1 is a top view of an audible alarm showing my new design;

FIG. 2 is a front elevation view thereof;

FIG. 3 is a bottom view thereof;

FIG. 4 is a rear elevation view thereof;

FIG. 5 is a side elevation view thereof; and

FIG. 6 is another side elevation view thereof.

I claim:

The ornamental design for an audible alarm, substantially as shown and described.
